SEWING MACHINE CONSTRUCTION

Peter F. Cencer and Fred Whiteman, Detroit, Mich., assignors to Leonore Gidion, special administratrix of the estate of Frank M. Gidion, deceased, Detroit, Mich.

Application September 9, 1950, Serial No. 184,027

6 Claims. (Cl. 112—210)

1

This invention relates generally to sewing machines and has to do more particularly with a sewing machine having novel means for automatically taking up the thread in the stitches in the material being sewed for producing tight stitches, and novel means for feeding the material through the machine as it is being sewed.

An object of the invention is the provision of a sewing machine having such novel construction that it automatically draws the stitches tight regardless of the thickness of the material being sewed, without any manual adjustment made for the purpose.

Another object is the provision of a sewing machine in which each stitch, as it is made, is drawn up so that the stitch just previously made is drawn tight, in such a manner that that portion of the previous stitch interconnected with the subsequent stitch is drawn up into the body of the fabric or other material being sewed, thereby effectively locking the stitches in place so that they cannot easily be ripped out.

A further object is the provision of a rock bar effective for transmitting drive from the driving means to the needle and thread take-up lever, and effective for releasing the thread nipper.

Another object is the provision of a hollow needle bar.

Another object is the provision of material feeding means actuated by a cam on the shaft which operates the looper.

A more specific object is the provision of a material feeding means including a feed member moved a fixed, predetermined extent and in a fixed path by the operating parts of the sewing machine, and a second movable feed member, with adjustable means interconnecting the two feed members, whereby the path and extent of movement of the second feed member can be adjusted according to the adjustment of the adjustable means, the second feed member having a feed dog for feeding the material through the machine.

A further object is the provision of a sewing machine of the character above referred to for making chain stitches having novel mechanism whereby, regardless of the tightness to which the stitches are drawn, puckering of the material sewed is prevented.

Other objects and advantages will become apparent upon reference to the following description and to the accompanying drawings wherein,

Figure 1 is a front elevational view of the sewing machine of the present invention;

Fig. 2 is an enlarged view oriented similarly to

2

Fig. 1, but with the portion of the housing nearest the observer removed;

Fig. 3 is a rear elevational view, with the portion of the housing nearest the observer removed;

Fig. 4 is a plan view of the sewing machine with the housing removed;

Fig. 5 is a bottom view of the base showing the operating parts mounted thereon;

Fig. 6 is a vertical sectional view taken on line 6—6 of Fig. 2;

Fig. 7 is an elevational view of the machine as viewed from the left-hand end of Fig. 2 with the housing in the foreground removed and the housing in the background in section;

Fig. 8 is a view similar to Fig. 7 with the operating parts in the positions assumed during a different portion of the cycle of operation;

Figs. 9 and 10 are detail views of members making up the feeding mechanism for feeding the material being sewed through the machine; and

Figs. 11 to 14, inclusive, are semi-diagrammatic views of the needle, a portion of the needle-driving mechanism, and looper in the positions assumed during various stages in the cycle of operation of the machine.

Referring now in detail to the drawings, the sewing machine will be described in various phases under appropriate sub-headings to facilitate understanding of the structure of the machine and its mode of operation.

The sewing machine illustrated in the present application is of the type that sews chain stitches, i. e., each stitch is looped through the previous stitch made, and includes a needle which penetrates the material being sewed, and a looper cooperating with the needle for looping successive stitches together; however, certain features of the invention are equally adaptable to sewing machines of other types.

Base

The sewing machine includes a base 16 in the shape of an inverted pan, having a table top 18 for supporting the operating parts of the machine and furnishing a surface for supporting the fabric or other material being sewed. The base 16 includes a surrounding skirt portion 20 having foot portions 22 for engaging the supporting surface on which the sewing machine is placed. The under surface of the base is open as will be referred to later. The top of the base 18 is provided with certain openings for receiving operating parts of the machine, as well as for receiving

securing means for mounting the operating parts of the sewing machine on the base.

Frame for supporting operating parts

The frame (Fig. 2) includes two main elements, one of which is a plate element 24 having a vertically disposed portion 26 extending transversely of the base adjacent to but spaced from the right-hand end. The plate element 24 has a turned over flange 28 for strengthening purposes and includes a horizontal foot portion 30 resting on and secured to the base. The end of the foot portion 30 spaced from the portion 26 is provided with an upstanding flange 32 which is closely adjacent the right-hand end of the machine.

The second main element of the frame consists of a plate element 34 which is provided with a transverse element or flange 36 secured to the element 24 as by welding or by other suitable means. The plate element 34 is vertically disposed and extends longitudinally of the machine from the plate element 26 terminating adjacent the left-hand end of the machine as clearly illustrated in Figs. 2 and 3. It will also be noted that the plate element 34 is supported by the upright portion 26 in elevated position with respect to the base.

Main drive

In the present illustrative embodiment a motor 38 which may be an electric motor is provided for driving the sewing machine. However, it will be understood that any suitable means for driving the machine may be employed. The motor 38 is mounted on the plate element 26 on the right-hand side of the latter and includes a driving shaft 39 on which is secured a driving pinion 40 meshing with a gear 42 mounted on a shaft 44. The shaft 44 is journaled in bearings, one of which is mounted in the plate element 26 and the other in the upstanding flange 32, the shaft 44 extending to the right of the flange 32 and provided on its outer end with a hand wheel 46 for the usual purpose. Also mounted on the driving shaft 44 adjacent the gear 42 is a second gear 48 of lesser diameter than the gear 42, the gear 48 meshing with another gear 50. The gears 42 and 50 project through a slot 52 in the top surface of the base of the machine (Fig. 5). The gear 50 is secured to a shaft 54 for rotation therewith, the shaft 54 being journaled in bearings 56 and 58 mounted on the underside of the top of the base. The bearing 58 is positioned adjacent a vertical plate 60 having a flange 62 secured to the underside of the base. The plate 60 supports the material feeding means as will be referred to in detail later. If desired, belt drive means may be employed instead of the gearing above described, suitable pulleys being provided on the respective shafts and suitable means being provided for producing properly timed drive between the various elements of the driving train.

Needle drive

A rock bar 64 (Figs. 2, 3 and 4) is provided for transmitting the drive from the motor to the needle and certain other parts of the sewing machine. The rock bar 64 takes the form of a rigid flat strip, the main portion of which is disposed on one side of the plate element 34, extending longitudinally of the machine with its flat side disposed generally vertically. The rock bar 64 includes two laterally extending arms 66 and 68 which are pivoted in lugs 70 and 72 ex-

tending substantially at right angles from the plate element 34, the two pivot points, of course, being in alignment. The arm 66 extends through an opening in the plate element 34 to the opposite side thereof. A pitman 74 is pivoted at one end to the extended end of the arm 66 by suitable means such as a screw 76 and at its other end is pivotally mounted eccentrically on the gear 48 by means such as a screw 78. Upon rotation of the gear 48 the pitman is reciprocated, resulting in swinging the arm 66 and thereby rocking the rock bar 64 and swinging the extended end of the arm 68 which also extends across the plate element 34 at the left-hand end thereof. The arm 68 serves the dual purpose of reciprocating the needle and forming a thread take-up lever both of which purposes will be referred to in detail later. The extended end of the arm 68 is provided with an aperture 80 (Figs. 7 and 8) for threading therethrough of thread employed in sewing, whereby the arm serves as a thread take-up lever.

Needle and mounting therefor

The needle 82 of the sewing machine is mounted in the lower end of a hollow needle bar 84 by means of a set screw 86 in the usual manner. The needle may be of any suitable known form and is provided with the usual eye at its lower end. The hollow bar 84 is mounted for vertical reciprocation in bearing sleeves 88 and 90, the former being mounted on a horizontal element 92 secured to the plate element 34 and the sleeve 90 being mounted on a turned over element or flange 94 also secured to the plate element 34. A stud 96 is fixedly secured to the hollow bar 84 at a point between the bearing sleeves 88 and 90. A pitman or link 98 is secured at its lower end to the stud 96 as by means of a screw 100 and pivotally secured at its upper end to the arm 68 as by means of a screw 102. At this point it should be noted that the point of connection between the pitman 98 and the arm 68 is at a position spaced inwardly from the extreme outer or free end to the arm 68 while the aperture 80 is adjacent the extreme end of the arm. Accordingly, the aperture 80, upon reciprocation of the arm 68, travels a greater distance than the pitman 98, for a purpose to be explained later.

The employment of a hollow bar for the needle enables the bar to be reciprocated substantially without vibration such as would occur in the case of a solid bar. The employment of a hollow bar is made possible because of the fact that the thread is not extended through the shank as in many machines but through other elements in by-passing relation to the shank, as will be explained in detail later.

Presser foot and mounting therefor

A presser foot 104 for engaging the material being sewed is in the form of a forked element having a slot through which the sewing needle is adapted to project. The presser foot itself may take any desired shape, but the present illustration includes a horizontal portion 105 adapted to directly engage the material being sewed, and upturned toe portions 106 effective for directing the material under the presser foot. The rear or trailing portion of the presser foot is provided with a U-shaped portion having upstanding flanges 108 into which extends the lower end of a mounting element 110. A pin 111 extends through the flanges 108 and element 110 by means of which the presser foot is pivotally mounted on the element 110 for limited rocking movement.

The mounting element 110 is mounted on a bar 112 as by means of a screw 114. The bar 112 is mounted for vertical reciprocation in bearing sleeves 116 and 118 mounted on the elements 92 and 94 referred to above in connection with the needle bar. Above the element 92 a collar 120 is fixedly secured to the bar 112 and a compression spring 122 is compressed between the collar 120 and the upper bearing sleeve 118 in surrounding relation to the bar for urging the shank and the presser foot downwardly.

For the purpose of raising the presser foot upwardly out of engagement with the material being sewed when it is so desired (as when material to be sewed is inserted into or removed from its position under the presser foot), a lever 124 is pivotally mounted on a pin secured to the collar 120, the lever 124 having camming surfaces engageable with the element 92 for so raising the bar and presser foot, and is also provided with an over-center surface for retaining the shank and presser foot in raised or elevated position when the lever is thrown to the appropriate position.

Thread feed and control

A spool of thread 126 is mounted in an opening 128 in the plate element 34. The means for mounting the spool includes a pin or spindle 130 pivotally mounted on an out-turned lug 132 formed on the plate element 34. The pin or spindle 130 is adapted to be swung outwardly about a vertical axis enabling the spool to be placed thereon and then swung inwardly so that its free end engages the plate element 34 positioning the spool in the opening 128 in such position that the spool extends on opposite sides of the plate element.

The thread 134 is threaded through a plurality of guides 136 fixedly mounted on the plate element 34, the guides conveniently being formed of wires secured to the plate element with loops in their extended ends for receiving the thread therethrough. The thread is also threaded through a pull-off finger 138 which is of a shape similar to that of the guides 136 but is mounted on the rock bar 64 and extends through an aperture 140 in the plate element 34. The pull-off finger 138 is disposed between pairs of the guides 136. Upon rocking of the rock shaft the pull-off finger 138 is swung vertically, resulting in pulling off thread from the spool in conjunction with other elements of the threading means.

A disk tension means 142 is disposed posterior to the guides 136 with respect to the movement of the thread from the spool to the needle. The disk tension 142 is best observed in Fig. 4 where it will be seen that it includes a threaded shank 144 threaded in an opening in the plate element 34. A compression spring 146 surrounds the shank 144 and engages a disk 148 which in turn engages a second disk 150, both loosely mounted on the shank and engageable with button 152 on the outer end of the shank. The two disks have convex circumferential portions facing each other for easy reception of the thread therebetween. The spring 146 urges the disks relatively into engagement with each other and prevents undue slipping of the thread between the disks, but is of sufficient yieldability to permit movement of the thread on application of a predetermined force on the thread. Turning the shank 144 in or out by means of button 152 increases or decreases, respectively, the compression on the

75

spring and accordingly adjusts the gripping action of the disks 148 and 150 on the thread.

Posterior to the disk tension means is an adjustable thread nipper 154 which also is best shown in Fig. 4. The nipper 154 includes a button 156 mounted on a shank 158 slidably mounted in a sleeve 160 threadedly mounted in an opening in the plate element 34. A compression spring 161 surrounds the shank in the sleeve, being compressed between nut element 162 fixed on the sleeve and a washer 163 on the shank. The spring urges the shank in a direction to move the button 156 into engagement with the nut element 162 for nipping or gripping the thread therebetween. The extended end of the shank 158 is adapted to be engaged by a bumper 164 mounted on the rock bar 64 upon rocking of the latter. The bumper 162 may be of any desired resilient material, such as rubber or a rubber-like product. Turning of sleeve 160 produces an adjustment thereof with respect to the plate element 34 for positioning the shank 158 closer to or farther from the bumper 164 for adjusting the timing of release of the nipper.

25 The thread is inserted between the button 156 of the nipper and nut element 162 and when the button is positioned as shown in Fig. 4, it retains the thread against feeding therethrough in normal operation of the machine and when a predetermined force is applied to the thread, but when a force in excess of the predetermined tension is applied, the thread can be drawn through the nipper. The nipper 154 is released upon downward rocking of the rock bar 64, i. e., upon the bumper 164 engaging the adjacent end of the shank 158 and thereby moving button 156 out of gripping engagement with the thread.

30 Posterior to the nipper 154 the thread is passed through the aperture 80 in the arm 68 and then 40 through an aperture in the element 92 and finally through the eye of the needle.

Housing

45 Most of the operating parts thus far described are enclosed within a housing indicated generally at 164 which is made up of three parts. The housing as illustrated in Figs. 1, 2 and 3, encloses all of the operating parts that are disposed above the base with the exception of the hand wheel 46, the lower ends of the needle and the presser foot and their mountings. The housing includes a shell section 166 made up of one piece on one side of the machine and two separate sections 168 and 170 on the other side. The portion 166 is secured at one end to the base 50 as by means of appropriate screws and at the other end to the plate element 34 by screw means 172. The housing section 168 is also secured to the base as by means of screws and the section 55 170 is secured to the other two sections by means of appropriate clips so arranged that the section 170 may be readily removed by the operator for the purpose of exposing certain operating parts of the machine.

60

Looper

65 Mounted on the shaft 54 on the underside of the base is a small looper indicated generally at 174 for rotation with the shaft. The looper includes a point 176 and a heel 178. Upon rotation of the looper the point 176 engages a thread loop formed by the needle 82 upon penetration of the needle through the material being sewed. The loop is carried around by the looper and finally cast off therefrom but a new loop is picked up before a previous loop has been cast off for

linking the loops together in a chain stitch which will be referred to hereinafter. The looper 174 is of a hard material for preventing nicking and scratching, being preferably composed of a copper-chrome alloy.

Adjacent the looper 174 and mounted on the shaft 54 is a cam 180 for actuation of the material feeding means. The cam 180 is cylindrical in shape, eccentrically mounted on the shaft.

Material feeding means

Mounted on the plate element 60 on the underside of the base is a pair of plates referred to for convenience as an auxiliary feed member 182 and a main feed member 184. The feed members are preferably fitted with their flat sides in engagement and both are provided with slots 186 through which a screw 188 extends, the screw being mounted in the plate element 60. The feed members 182 and 184 are therefore mounted for vertical swinging, and for longitudinal sliding movement. The auxiliary feed member 182 is provided with a notch 190 open at the top, in which the cam 180 is disposed, the horizontal dimension of the notch being substantially equal to the diameter of the cam. At the free or swinging end of the auxiliary feed member 182 is a cut out portion 192 in which is operatively disposed an enlarged head 194 of a link 196 connected to an arcuate lever 198 having a slot 200 therein. The lever 198 is pivoted at 202 on the plate 60 for swinging in a vertical plane parallel with the planes of movement of the members 182 and 184.

The main feed member 184 is provided with a horizontally arranged slot 204 through which the cam 180 projects. The slot 204 has a vertical dimension substantially equal to the diameter of the cam 180 but has a horizontal dimension of substantially greater extent. At the extreme or swinging end of the element 184 is a cut out portion 206 for pivotally receiving an enlarged head 208 of a link 210, the opposite end of the link having a laterally projecting stud 212 operatively disposed in the slot 200.

A yoke or U-shaped element 214 (Figs. 5, 7 and 8) is disposed, with its legs straddling the plate 60 and feed members 182 and 184, one of the legs 216 being mounted by means of screw 218 upon the plate element 60 for vertical swinging. The other leg 220 is provided with a diagonal slot 222 (Figs. 7 and 8) for receiving a pin 224 on the link 210.

The leg 216 is provided with vertically spaced lugs 226 (Fig. 5) for receiving one arm 228 of a bell crank lever 230 pivotally mounted at 232, the other arm 234 being pivotally connected at 236 to a rod or link 238 extending toward the opposite end of the base where a thumbscrew and operating knob 240 are secured and which extend through the base as indicated in Figs. 1 and 2 for manipulation by the operator for adjusting the length of the threads as will be explained later. The thumbscrew 240 may be turned in to gripping engagement with the base for securing it in adjusted position whereby the material feeding means is retained in adjusted position.

Mounted on the main feed member 184 as viewed in Figs. 7 and 8 is a feed dog 242 which includes an arm secured to the member 184 by means of a screw 244 for angular adjustment of the feed dog. The feed dog extends upwardly and has a horizontal portion 246 composed of three segments having gripping teeth 248. The

teeth 248 are adapted to extend through slots 250 in a plate 252 mounted over a large opening in the top surface of the base and secured therein as by means of screws 254. The plate 252 also includes an aperture for projection therethrough of the sewing needle. The teeth 248 are adapted to grip the material being sewed in conjunction with the presser foot 106 for feeding the material through the machine as it is sewed.

10

General operation

The driving motor upon operation thereof, through the gearing referred to, rotates the shaft 54 for rotating the looper 174 and the material feeding means through the cam 180; also, the pitman 74 is caused to reciprocate, which thereby rocks the rock bar 64. Upon rocking of the rock bar the arm 68 is reciprocated vertically and the latter, acting through pitman 98, reciprocates the needle bar 84 and the needle 82. The needle is projected downwardly as shown in Fig. 11 and penetrates through the material being sewed, which is indicated at 256. A loop 258 is formed below the material and upon rotation of the looper 174 as referred to above, point 176 thereof projects into the loop and upon continued rotation of the looper, the loop 258 is carried onto the looper. Further rotation of the looper causes the loop to be cast off but before each loop is cast off, a new loop is picked up by the point and carried through the previous loop which is being cast off. This operation results in a chain stitch indicated generally at 260 in Figs. 11 to 14. The material is fed through the machine between each two successive stitches for properly spacing the stitches in the material, as will be described later.

Attention is now directed to the novel arrangement and relationship of the parts of the sewing machine for drawing the stitches tight; the thread take-up lever has a greater throw than the movement of the needle, whereby a greater amount of thread is necessary to accommodate the movement of the take-up lever than would be necessary to accommodate the movement of the needle; the main supply of thread is retained against paying out during a portion of the retraction movement of the take-up lever, whereby the extra amount of thread necessary to accommodate the movement of the take-up lever is drawn from that portion of the thread making up the stitches, resulting in the stitches being drawn tight.

The thread nipper is normally effective for preventing paying out of thread from the main supply, but it will permit thread to be payed out upon sufficient tension being applied to the thread; for example, the nipper will normally restrain paying out of the thread so as to effect tightly drawing of a stitch, but thereafter it will permit paying out of thread upon sufficient force being applied to the thread; hence in the case of thick material being sewed, the nipper will effect tight drawing of the stitches while permitting paying out of the greater amount of thread necessary to produce the stitches as compared with the case of thin material, and as a consequence the stitches are drawn tight in materials of all thicknesses without the necessity of manual adjustment made for the purpose.

Upon upward rocking of the rock bar 64, the bumper 164 is moved out of engagement with the shank 158 of the nipper 154, permitting the button 156 to grip the thread; also upon upward rocking of the rock bar, the pull-off finger 138

75

swings downwardly and draws thread from the spool 126, this being accomplished by reason of the fact that the thread is gripped by the nipper. As a result, a portion of the thread is payed out for feeding toward the needle at a later step in the operation of the machine. When the arm 68 approaches its uppermost position, the nipper 154 is released upon downward rocking of the rock bar 64 so that the arm 68 forming a take-up lever is enabled to draw up slack in the thread previously produced by the pull-off finger 138, whereby the thread can be payed out or fed to the needle upon downward movement of the take-up lever.

Upon downward movement of the needle the 15 needle carries the thread through the material being sewed, and as the needle is moved downwardly the take-up lever 68 also moves downwardly permitting slack thread, previously payed out by the take-up lever, to be drawn down by the needle. The stitch is then formed as above described, and upon upward movement of the needle the take-up lever 68 also moves upwardly a distance greater than the upward movement of the needle. During the first portion of the upward movement of the take-up lever the nipper 154 is in thread gripping position, but just before the take-up lever reaches its uppermost position, downward rocking of the rock bar releases the nipper which remains released until after the take-up lever begins its downward movement. Because the take-up lever moves a distance greater than the movement of the needle, and also because the thread is gripped by the nipper in the first portion of the upward movement of the take-up lever, the amount of thread necessary to accommodate the greater movement of the take-up lever is drawn from that portion of the thread making up the stitch in the fabric and, consequently, the stitch is drawn tight. During the first portion of the upward movement of the take-up lever the looper is passing downwardly. In Figure 13 one portion of the looper in its downward movement is indicated, while the take-up lever is moving upwardly. The take-up lever and the looper coact to draw the thread tight in the stitch and, in so doing, tension is applied directly to the strand 260 and the tension or force applied is transmitted through the last stitch made and, finally, into the loop 262, drawing the latter tight and drawing the bight of the loop of the previous stitch upward into the body of the fabric. Such condition is shown at 264 in Figure 14. As a result of such condition the stitches are secured in the fabric, and ripping out of the stitches is rendered difficult.

Special attention is called to the fact that the free or swinging end of the take-up lever 68 moves a distance greater than the movement of the needle, and this relationship is effective for drawing the stitches tight, and is in contrast to that arrangement in previously known machines in which the retraction of the needle itself draws the stitches tight.

As mentioned above, the bumper 164 engages the shank 158 just before the take-up lever reaches its uppermost position, and releases the nipper whereby the final upward movement of the take-up lever pays out thread from that portion which was previously payed out by means of the pull-off finger 138. After the take-up lever begins its downward movement, the nipper is again closed for the succeeding stitch.

The arrangement and timing are pre-set for sewing material of the thinnest gauge that may 75

be desired, and with such presetting, materials of any desired greater thickness within a wide range, can be sewed, without any adjustment being made for the purpose.

5 The presser foot 104 is in engagement with the material being sewed while the stitch is being formed and, because of the downward pull on the strand 260 (Figure 13), the pressure transmitted to the fabric forces the fabric downwardly against the wide area top surface of the base and this fact, in conjunction with the presser foot bearing on the material, prevents the material from puckering which may otherwise be caused by the tension applied to the thread in drawing the stitches tight.

The means for feeding the material being sewed through the machine is coordinated with the cycle of operation of the machine in such a manner that the material is moved while the nipper is released, so that the thread necessary to accommodate the movement of the material is made readily available; the feeding means is adjustable, whereby the extent of movement of the material can be varied for varying the length of the stitches; as a result, stitches will be produced as previously referred to in the case of materials of all thicknesses, with no other adjustment than that necessary for adjusting the material feeding means.

Upon rotation of the shaft 54 and consequent rotation of the cam 180 the auxiliary feed member 182 is caused to follow an essentially horizontal sliding movement. The horizontal sliding movement results in reciprocation of the link 196 to effect swinging of the lever 198; due to the swinging movement of the lever 198, the free end of the member 182 will have a vertical component of movement, but this will be slight. The swinging movement of the lever 198 causes horizontal sliding movement of the main feed member 184. Also, the cam 180 causes vertical swinging of the member 184 about the screw 188, and the main feed member 184 therefore has a combined vertical and horizontal movement which follows a path that is essentially rectangular in outline. Upon upward swinging of the feed member 184 the feed dog 246 engages the material being sewed; thereafter, the feed dog is moved horizontally (to the left as viewed in Figures 7 and 8), and in doing so, feeds the material through the machine. After thus moving the material, the feed dog is moved downwardly away from the material, and then back horizontally to starting position. The feeding action takes place, obviously, when the needle is retracted from the material as illustrated in Figure 7, and this action also takes place when the nipper 154 is released so that thread will be payed out to accommodate the feeding movement of the material. It will be noted that the feeding of the material occurs after each stitch has been formed and tightened.

60 For purposes of adjusting the length of stitch the knob 240 is slid one way or the other causing the rod 238 to be moved which actuates the bell crank 230 and swings the yoke 214 upwardly or downwardly. The movement of the yoke adjustably positions the stud 212 in the slot 200 at respective positions closer to or farther away from the pivot axis 202 of the lever 198. Thus, the longitudinal sliding movement of the plate element 184, and consequently of the feed dog 246, is controlled by the position of the stud 212, namely, the nearer the pivot axis 202 the less horizontal the movement of the feed dog, and vice versa. The extent of each increment of the

feeding movement of the material being sewed is controlled and thus the length of stitches controlled. The knob 240 can be secured in the desired adjusted positions for maintaining the desired length of stitch, as by turning it into gripping engagement with the base of the machine.

It will be seen from the above that the operation of the stitch forming mechanism of the machine operates the same for all adjustments of the feeding mechanism, that is, the stitches will be drawn tight by the take-up lever in conjunction with the looper to the same extent regardless of the length of stitches. In view of the foregoing in which the various operations and timing relationships were specifically described, it may be stated in summary that the stitches are drawn tight regardless of the thickness of the material being sewed. The length of stroke of the needle and the extent of movement of the take-up lever are respectively the same for all thicknesses of material. In the case of thick material each stitch is drawn tight sooner than in the case of thin material, and in the case of thick material the added amount of thread necessary for the stitch is caused to be payed out by the take-up lever, which forcibly draws the thread through the nipper even though the nipper is in thread gripping position, the nipper permitting the thread to be drawn for this purpose due to the extra tension or force applied.

Two important features of the invention are to be noted: (a) the arrangement and interrelationship of the operating elements, i. e., needle, looper, feed of thread, and retraction of thread by the take-up lever, and (b) the timing between the operations of the elements in the operation of the machine. These two features result in effective stitch tightening, and in feeding the material through the machine without puckering; also puckering of the material is prevented during the stitch tightening operation. The take-up lever and looper together draw on the thread to tighten a stitch while the nipper is closed; if thick material is being sewed, the extra thread necessary is drawn or "stolen" through the closed nipper. This action takes place while the needle is retracted from the material. The material is fed through the machine while the nipper is open, preventing puckering of the material during that operation. Puckering of the material during the stitch tightening operation is prevented because of the fact that the looper, in its downward movement, is the proximate instrument which tightens the stitch as more fully explained above.

The operation of the elements is positively timed from a single main, positive drive.

While we have herein shown and described a specific embodiment of the invention it is to be understood that minor changes can be made within the scope of the appended claims.

We claim:

1. In a sewing machine, a support, a rock bar pivotally mounted on said support on a horizontal axis, means for rocking said rock bar, an arm extending laterally from said rock bar, said arm swinging in generally vertical directions on rocking of said rock bar, a reciprocable needle means supporting said needle and connected with said arm at a point on said arm spaced inwardly from the extended end of the arm, said needle being reciprocated on swinging of said arm, means guiding said needle for vertical reciprocation, means cooperating with said needle for forming stitches, the extended end of said arm

having an opening for receiving thread, the extended end of said arm serving as thread take-up means in cooperation with said stitch forming means.

5 2. In a sewing machine having a horizontal surface for supporting material to be sewed, and means for sewing the material, a pair of plate-like members with their flat sides abutting positioned below the material and secured at one end for vertical swinging movement and for horizontal sliding movement, a first one of said members having a vertical slot therein, a second one of said members having a horizontal slot therein, a feed dog mounted on said second member, single cam means operably disposed in said slots, said cam means being operative for swinging said second member vertically and moving said first member horizontally, a lever pivoted adjacent the free ends of said members for swinging in a vertical plane parallel with the planes of movement of said members, means interconnecting said first member with said lever for transmitting horizontal movement from the member to said lever for swinging the lever, and means interconnecting said lever and said second member for transmitting horizontal movement from said lever to said second member.

3. In a sewing machine having a horizontal surface for supporting material to be sewed, and means for sewing the material, a pair of plate-like members with their flat sides abutting positioned below the material and secured at one end for vertical swinging movement and for horizontal sliding movement, a first one of said members having a vertical slot therein, a second one of said members having a horizontal slot therein, a feed dog mounted on said second member, single cam means operably disposed in said slots, said cam means being operative for swinging said second member vertically and moving said first member horizontally, a lever pivoted adjacent the free ends of said members for swinging in a vertical plane parallel with the planes of movement of said members, means interconnecting said first member with said lever for transmitting horizontal movement from the member to said lever for swinging the lever, means interconnecting said lever and said second member for transmitting horizontal movement from said lever to said second member, and means for adjustably moving the point of connection between said second member and lever toward and from the pivot axis of said lever for varying the extent of horizontal movement of said second member.

4. In a sewing machine having a horizontal surface for supporting material to be sewed, and means for sewing the material, a pair of plate-like members with their flat sides abutting positioned below the material and secured at one end for vertical swinging movement and for horizontal sliding movement, a first one of said members having a vertical slot therein, a second one of said members having a horizontal slot therein, a feed dog mounted on said second member, single cam means operably disposed in said slots, said cam means being operative for swinging said second member vertically and moving said first member horizontally, a lever pivoted adjacent the free ends of said members for swinging in a vertical plane parallel with the planes of movement of said members, a link pivotally interconnecting said first member and said lever, said lever having a slot therein, a link pivotally connected at one end to said second member and having its other end slidably in said slot in said

lever, and means operative for adjustably positioning the extended end of said link in said slot in positions respectively adjacent to and remote from the pivot axis of said lever for varying the extent of horizontal movement of said second member.

5. In a sewing machine, a frame, a rock bar pivotally mounted on said frame in a horizontal axis for rocking movement, a lateral arm extending from said rock bar and swingable generally vertically in response to rocking of the rock bar, a reciprocable needle supported by said frame for reciprocation vertically toward and from a sewing station, said needle having operative connection with said arm at a point on the arm spaced inwardly from the extended end of the arm for reciprocation of the needle in response to swinging of the rock bar, the extended end of said arm having an opening for thread and being operative as a thread take-up means, the extended end of said arm having a greater range of vertical movement than the point of connection between said needle and the arm in the swinging movements of the arm, a thread nipper on the side of said take-up means remote from 25 the needle, means biasing said nipper into engagement with thread therein, and means operated by said rock bar positioned for releasing said thread nipper in the latter portion of re-tracting movement of the needle away from the 30 sewing station.

6. In a sewing machine, a needle mounted for reciprocation toward a sewing station and in re-tracting movement therefrom, means for supporting a supply of thread for supplying thread to the needle, a thread nipper between said thread supply and said needle, means biasing said nipper to position for engaging thread therein, reciprocable thread take-up means between said nipper and said needle, a rock bar mounted for rocking movement, connections between said rock bar and said needle and said take-up means for reciprocating the needle and take-up means in unison in the same directions in response to rocking of the rock bar, means operated by said rock bar in response to rocking thereof positioned for releasing said nipper in the latter portion of the re-tracting movement of said needle, and means for rocking said rock bar.
